ADJUSTABLE AIR DIFFUSER AND DAMPER
John P. Dry, P.O. Box 797, Winters, Tex.
Filed Aug. 29, 1961, Ser. No. 134,739
1 Claim. (Cl. 98—46)

The present invention relates to an adjustable air diffuser and damper.

The primary object of the present invention is to provide an adjustable air diffuser and damper which is adapted to be used for completely eliminating the necessity of an additional damper to regulate the amount of desired air, and wherein the present invention enables an air conditioning or heating engineer to balance the system so that the user may open the diffuser to the balance position only or close the outlet completely as desired or required.

Another object is to provide an adjustable air diffuser and damper which is constructed so that the diffuser can be fastened inside the ducts and this is not possible with conventional diffusers without the addition of an installation ring or separate damper, and wherein the diffuser of the present invention can be produced at a much lower cost than the conventional diffuser and damper combination, and the present invention also eliminates the necessity of duct fitting to increase the outlet size since most conventional diffusers require a larger opening than the supply duct.

Another object is to provide a device of the character described which will handle the same amount of air as the supply duct without the transition fitting required for most conventional diffusers, and wherein the present invention utilizes a simple push coaction which permits the user to operate the diffuser regardless of any mechanical knowledge he or she may or may not have, and wherein the adjustment is clearly in view so that it is not necessary to climb on a ladder and look through the diffuser to see if the damper is opened or closed.

Another object is to provide an apparatus of the character described that may be utilized speedily and with precision by even inexperienced operators.

Further objects and advantages are to provide improved elements and arrangements thereof of the device of the character described that is economical to produce, durable in form, and conducive to the most economical use of materials and uniformity of members formed therefrom.

Still further objects and advantages will become apparent from the subsequent description and specification.

In the drawings:

FIGURE 1 is a top plan view of the adjustable air diffuser and damper of the present invention, with parts broken away.

FIGURE 2 is a sectional view taken on the line 2—2 of FIGURE 1, and showing the present invention mounted in a ceiling or the like, and showing the device in closed position.

FIGURE 3 is a bottom plan view taken of the apparatus shown in FIGURE 2, and with parts broken away and in section.

FIGURE 4 is a view generally similar to FIGURE 2 but with the device opened.

FIGURE 5 is a sectional view taken on the line 5—5 of FIGURE 2.

FIGURE 6 is an elevational view of the gasket or washer, and FIGURE 6 being on a reduced scale.

Referring in detail to the drawings, the numeral 10 indicates a portion of a wall, ceiling or the like, and the wall or ceiling 10 is provided with an opening 11, FIGURE 2. The numeral 12 indicates a conventional duct which is arranged contiguous to the ceiling 10, and according to the present invention there is provided an adjustable air diffuser and damper which is indicated generally by

2

the numeral 14, and the air diffuser and damper 14 includes a ring member 13 which embodies a wall member 15 which may have an annular formation, the wall member 15 extending through the opening 11 in the ceiling 10.

- 5 The ring member 13 further includes a base portion or base member 16 which embodies an annular wall section 17 that is snugly seated in the wall member 15, and the wall section 17 is secured as by welding to the wall member 15. The base portion 16 further includes a flared section 18 which merges into an annular shoulder 19, and the shoulder 19 has an edge portion 20 which abuts or engages the ceiling 10, FIGURES 2 and 4.

As shown in FIGURE 1 for example, there is provided a supporting structure which is indicated generally by the numeral 21, and the supporting structure 21 includes a pair of similar support members 22 which have outwardly disposed flanges 23 that are secured as by welding to the inner surface of the wall member 15, and the support members 22 further include straight portions 24 as well as inwardly disposed flat sections 25, and the flat sections 25 are provided with intermediate offset portions 26, and a pair of opposed offset portions 26 coact with to define therebetween a rectangular bracket or trackway 27.

The numeral 28 indicates a channel which is adjustably mounted in the bracket or trackway 27, and the channel 28 has a cross section which conforms to the cross section of the bracket 27, and there is provided in axial alignment on one flange of the channel 28 a plurality of spaced apart apertures or openings 29 for a purpose to be later described. The numeral 30 indicates a spring element which is affixed within the bracket 27 in any suitable manner, and the spring member 30 is adapted to bear against the channel 28 to exert the desired or proper amount of pressure on the channel 28.

The numeral 31 indicates a spring clip which includes a first portion 32 that is adapted to engage the apertures 29 in the channel 28, and the spring clip 31 further includes a second or arcuate portion 33 which provides a hand grip, and the spring clip 31 further includes a third portion 34 which is provided with an intermediate offset section 35, FIGURE 1.

A lip or base element 36 is secured as by welding to an end of the channel 28, FIGURE 2, and the numeral 37 indicates a plate which has a formation shaped to a portion of a sphere, and there is provided a securing element or screw or bolt 38 which extends through the lip 36 and into engagement with a manually engageable knob 39. The numeral 40 indicates a gasket or washer which is made of yieldable material, and the gasket 40 is interposed between the ceiling 10 and base portion 16 as shown in the drawings.

From the foregoing, it is apparent that there has been provided an adjustable air diffuser and damper, and in use with the parts arranged as shown in the drawing, it will be seen that the ring member 13 is adapted to have its wall portion 15 extended through an opening such as the opening 11 in the ceiling 10, whereby with the duct 12 arranged as shown, the inner portion of the ring member will communicate with the duct 12, and the duct 12 may be of the type which is carrying warm or cool air depending upon whether each opening is being heated or cooled. The supporting structure 21 includes the members 22 which are fastened as by welding to the inner surface of the wall member 15, and inner portions of the members 22 are shaped to define the trackway 27 in which is mounted the adjustable tube 28, and the plate 37 is affixed to the channel 28 as at 38, and the knob 39 is adapted to be manually gripped so that by simple push pull action the plate 37 can be adjusted as desired or required. For example the plate 37 can be positioned in closed position relative to the base portion 16, as for example as shown

in FIGURE 2, or else the plate 37 can be moved to opened position as shown in FIGURE 4.

The spring element 30 helps exert sufficient pressure on the channel 28 so as to permit the tube 28 to move with the desired degree of facility, and the plurality of openings 29 and tube 28 are adapted to receive the portion 32 of the spring clip 31 whereby the spring clip 31 provides a means for helping to retain the parts such as the plate 37 immobile in their different or adjusted positions.

The parts can be made of any suitable material and in different shapes or sizes.

Minor changes in shape, size and rearrangement of details coming within the scope of the invention claimed may be resorted to in actual practice, if desired.

What is claimed is:

For use with a ceiling having an opening therein, there being a duct contiguous to said opening, an adjustable air diffuser and damper comprising a ring member embodying an annular wall member adapted to project through the opening in said ceiling, a base portion including an annular wall section snugly seated in said wall member and secured thereto, a yieldable gasket adapted to be interposed between said ceiling and said base portion, said base portion further including a flared section merging into an annular shoulder, said shoulder having an edge portion adapted to abut and engage said ceiling, a supporting structure including a pair of spaced apart support members having flanges on their outer ends secured to the inner surface of said wall member, said support members further including straight portions and inwardly disposed flat sections that are provided with intermediate offset por-

tions, said offset portions coacting to define therebetween a rectangular housing having opposed open ends disposed with one open end uppermost and the other open end lowermost, a vertically disposed channel adjustably mounted in said housing for upward and downward movement, said channel having a cross section configuration conformably shaped to the cross section of said housing, a spring element affixed to said housing for engaging said channel, said channel having a plurality of spaced apart axially aligned apertures, a spring clip having a first portion adapted to selectively extend through any one of the apertures in said channel above said housing and to engage the upper end of said housing so as to limit downward movement of said channel in said housing, said spring clip further having a curved second portion providing a hand grip portion, a base element carried by the lower end of said channel, a plate having a configuration of a portion of a sphere disposed below and adjacent said base element, a knob exteriorly of said plate, and a fastening element extending through said base element and knob securing said plate to said channel.
